(57) **CLAIM**

The ornamental design for an enclosure for a timer, as shown and described.

DESCRIPTION

FIG. 1 is a top, right front perspective view of an enclosure for a timer showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The structural features depicted by broken lines in the drawings have been shown for the purpose of illustrating portions of the enclosure for a timer that form no part of the claimed design.
